UNITED STATES PATENT OFFICE.

GEORGE FREDERICK NEWTON, OF PROVIDENCE, RHODE ISLAND, ASSIGNOR TO UNITED STATES FIRE PROTECTION COMPANY, OF PROVIDENCE, RHODE ISLAND, A CORPORATION OF RHODE ISLAND.

AUTOMATIC SPRINKLER.

Application filed March 16, 1925. Serial No. 15,959.

My invention has reference to an improvement in fire extinguishing devices and more particularly to an improvement in automatic sprinklers, as used in automatic sprinkler systems.

The object of my invention is to improve the construction and operation of automatic sprinklers and my invention pertains more particularly to that form of automatic sprinklers known as lever sprinklers.

Further objects of my invention are to reduce the cost of construction and improve the operation of automatic lever sprinklers thereby producing an automatic sprinkler that is more positively locked under normal, non-fire conditions and more quickly released under fire conditions, than has heretofore been done.

My invention consists in the peculiar and novel construction of an automatic lever sprinkler, said sprinkler having details of construction, as will be more fully set forth hereinafter and claimed.

Figure 1 is a side view of my improved automatic lever sprinkler, showing my improved adjustable deflector, in section.

Figure 2 is an edge view of Figure 1 and showing a face view of my improved fusible link.

Figure 3 is a central transverse sectional view through the cover of the valve head.

Figure 4 is a central transverse sectional view through the body of the valve head and showing the cover and springs in their normal positions, in broken lines.

Figure 5 is a side view of the cone shaped spiral spring of the valve head.

Figure 6 is a central transverse sectional view through the spring washer of the valve head.

Figure 7 is a face view of the fusible link member of the sprinkler.

Figure 8 is a central sectional view of the fusible link member, taken on line 8, 8, of Figure 7.

Figure 9 is a sectional view, similar to Figure 8, of a modified form of fusible link member.

Figure 10 is a central detail sectional view of the central position of Figure 8, and

Figure 11 is a face view of the semi-circular retaining members, as used in the modified form of fusible links, shown in Figure 9.

Figures 3, 4, 5, 6, 7, 8, 9 and 11, are en-

larged and Figure 10, still further enlarged, to more clearly show my invention.

In the drawing, 1 indicates the body of an automatic sprinkler having a screw-threaded tubular shank 2, 3 a yoke with a valve seat 4 and arms 5, 5, curving to a hub 6. A screw 7 is screw-threaded through the hub 6 and has the usual recessed inner end 8.

9 indicates my improved valve head which is in the form of a round shallow box on the valve seat 4 and it is constructed to have a body member with an inner straight central stud 10 and a cover 11 with a central recess in its top and an inner central tubular stud 12 which fits over the inner central stud 10 of the body member, of the valve head 9 and forms a guide for the cover. A cone shaped spiral spring 13 and a spring washer 14, as shown in Figures 5 and 6 respectively, are in the valve head 9, as shown in full and broken lines in Figure 4, and held in place, in their contracted positions, by the cover 11, when the valve head is on the valve seat 4, in the sprinkler.

15 indicates my improved adjustable deflector which consists of a body member 16 in the form of a flat disk having a screw-threaded periphery 17 and a central screw-threaded hole 18, whereby the body member 16 is secured to the sprinkler by screwing it onto the screw 7, against the hub 6. 80 A rim 19 having a series of bent fingers 20, 20, is screw-threaded onto the screw-threaded periphery 17, of the body member 16, thereby completing the deflector, as shown in Figure 1. By turning the rim 19 on the body member 16, the rim, which is the water spreading part of the deflector, is adjusted towards or away from the stream of water, thereby compensating for different water pressures.

Intermediate the hub 6 and the valve head 9 are levers 21 and 22, each lever having a hook shaped outer end 23. These levers have the usual inner end construction to engage with the screw 7, the valve head 9 and off center with each other, as shown in Figure 1.

24 indicates my improved fusible link member of the sprinkler. This fusible link member 24 is circular in form and consists of an outer disk 25 having a raised inclined annular edge 26, a hook hole 27, for the hook end 23 of the lever 21, a hook slot 28, for the hook end 23 of the lever 22, a central hole 29

in which is a small tube 30, which acts as a disk separating element. At each side of and on a central line with the central hole 29 are depressions 31 and 32. In the 5 depression 31 are two small rolls 33, 33, and in the depression 32 are two small off center toggle joint members 34, 34, and extending around the depressions is a concentric raised annular rib 35. Soldered centrally to the 10 back of the disk 25 is a sunken washer 36 the central hole in the washer 36 coinciding with the hole through the tube 30. An inner disk 37 is constructed to have an annular groove 38 for the annular rib 35 and a 15 soldered washer 36, otherwise the construction is the same as the outer disk 25. This inner disk 37 fits into the outer disk 25 and the small central tube 30, is smaller than the central holes 29, 29, in the disks. All of the 20 parts of the fusible link are secured in place and the entire inner surfaces of the two disks are secured together by solder 39, as shown in Figure 8.

In the modified form, shown in Figure 9, 25 the outer disk 25 has an annular groove 40, corresponding to the annular groove 38 in the inner disk 37, thereby forming a round annular bore 41, in which are soldered two semi-circular wire retaining members 42, 42, 30 shown in Figure 11.

By this construction all of the parts of the fusible link member are strongly secured together, thereby producing a fusible link member that will stand an extremely high 35 water pressure and that is also extremely sensitive under fire conditions. The raised inclined annular edges 26, the annular rib 35, the rolls 33, 33, the central tube 30, and the toggle joint members 34, 34, under fire 40 melting conditions, will quickly force the disks apart, thereby eliminating slow creeping of the disks. The spring action of the valve head 9 operates to compensate for expansion and contraction of the frame of the 45 sprinkler and also assists in a quick operation of the sprinkler. In the modified form of fusible link, shown in Figure 9, the wire retaining members 42, 42, also assist in forcing the disks apart when the solder melts.

50 When under fire conditions the solder 39 melts, the pressure of the water on the valve head 9 and the levers 21 and 22 will cause the parts of the fusible link to fall apart and the parts of the valve head and the 55 levers to separate and fall out of the sprinkler and the water will pass unobstructed to the deflector 15 from which it is distributed onto the fire.

In practice I find that the central tube 30, 60 lying as it does crosswise of the two disks, acts to firmly hold the disks against creeping of the disks and it also acts to quickly force the disks apart under fire melting conditions, and that this sprinkler will stand 65 an extremely strong water pressure without

leaking and at the same time is extremely sensitive in operation under fire conditions.

Having thus described my invention I claim as new:—

1. In an automatic sprinkler, a fusible link 70 member in the form of an outer and an inner disk, each disk having a central hole, a tube soldered to the disks in the central holes, the inner disk having a circular groove and the outer disk having a circular rib soldered in the circular groove, each disk having coinciding inclined annular peripheries soldered together, and means for securing the fusible link to the levers of an automatic 75 sprinkler.

2. In an automatic sprinkler, a fusible link member consisting of outer and inner disks soldered together, each disk having a central hole, a tube soldered to the disks in the central holes, a sunken washer soldered centrally to each disk, means forming a cavity between the disks, toggle joint members soldered to the disks in the cavity, an annular groove in one disk, an annular rib on the other disk and soldered in the annular 90 groove, each disk having inclined coinciding annular peripheries soldered together and means for securing the fusible link member in its operative position in an automatic 95 sprinkler.

3. In an automatic sprinkler, a valve head in the form of a round shallow box, said valve head having a body member with a central stud, a cover having a central tubular stud which goes over the central stud in the body member and forms a guide for the cover to hold the cover in place, a spring washer in the body member, a cone shaped spiral spring in the body member and means for holding the valve head in its operative 100 position on the valve seat of an automatic sprinkler, for the purpose as described.

4. In an automatic sprinkler, a valve head in the form of a round shallow box, said valve head having a body member with a central stud, a cover having a central tubular stud which fits over the central stud in the body member, a spring member in the body member, a spiral spring in the body member, said spiral spring being cone shaped 110 when not under spring tension, said central stud in the body member, guiding centrally the spiral spring and the spring member into the body member and also guiding centrally, the cover onto the body member.

5. A fusible link member for automatic 120 sprinklers, said link member consisting of two plates soldered together, the plates having central coinciding cylindrical holes, on an axial line with the plates, a tubular plate separating member in said holes and contacting with both plates, said tubular plate separating member extending crosswise of the plates and on a line with the axis of the plates and members on the plates over the 125

ends of the tubular plate separating member.

6. In an automatic sprinkler, a dish shaped deflector formed of inner and outer parts, said inner part being disk shaped and forming the bottom of the deflector and having a screw-threaded periphery and said outer part being in the form of an inclined rim having a series of bent peripheral fingers and screw-threads in screw-threaded engagement with the screw-threaded periphery of

the bottom member, whereby the rim member is adjustably secured to the bottom member of the deflector and means for securing the bottom member of the deflector to an automatic sprinkler, for the purpose as described. 15

In testimony whereof, I have signed my name to this specification.

GEORGE FREDERICK NEWTON.
